Primary Examiner — Charles Hanson(74) *Attorney, Agent, or Firm* — Calfee, Halter & Griswold LLP(57) **CLAIM**

We claim the ornamental design for a wheelchair table, as shown and described.

DESCRIPTION

FIG. 1 is a top perspective view of a first embodiment of a wheelchair table of the new design;

FIG. 2 is a top plan view of the wheelchair table of FIG. 1; FIG. 3 is a bottom plan view of the wheelchair table of FIG. 1;

FIG. 4 is a left side elevational view of the wheelchair table of FIG. 1;

FIG. 5 is a right side elevational view of the wheelchair table of FIG. 1;

FIG. 6 is a rear elevational view of the wheelchair table of FIG. 1; and,

FIG. 7 is a front elevational view of the wheelchair table of FIG. 1.

The broken line showing is included for the purpose of illustrating portions of the wheelchair table that form no part of the claimed design.

1 Claim, 5 Drawing Sheets(56)
